UNITED STATES PATENT OFFICE.

ALBERT L. CLAPP, OF BRAINTREE, MASSACHUSETTS, ASSIGNOR TO HIDE-ITE LEATHER COMPANY, OF BOSTON, MASSACHUSETTS, A CORPORATION OF MAINE.

PROCESS FOR THE PRODUCTION OF LEATHER-BOARD STOCK.

1,063,958.

Specification of Letters Patent.

Patented June 10, 1913.

No Drawing.

Application filed January 4, 1911. Serial No. 600,724.

To all whom it may concern:

Be it known that I, ALBERT L. CLAPP, a citizen of the United States, residing at Braintree, in the county of Norfolk and State of Massachusetts, have invented certain new and useful Improvements in Processes for the Production of Leather-Board Stock, of which the following is a specification.

10 My present invention pertains to an improved process of producing stock for leather-board, and to the board made from such stock.

15 The board formed from the stock produced by the method hereinafter set forth in detail is waterproof and has a waterproofing oil, fat, wax or the like equally distributed throughout its body during the process of manufacturing the stock, such waterproofing 20 medium being preferably carried into and distributed throughout the body of the stock (which is usually formed of shredded fibrous leather) by a suitable vehicle, ordinarily in the form of a fine powder, with which it is 25 mixed prior to introduction into the stock. The oil or other substance employed may, however, though not so great an advantage, be mixed with the beater stock in the beater engine while the same is being 30 beaten up.

The introduction of the oil-carrying vehicle, which is loaded with the oil or other equivalent material, into and throughout the fibrous body of the board has the effect of 35 producing a board equally waterproof throughout, for as the sheets are dried after being formed the oil spreads from the vehicle throughout the board. This is a manifest advantage and, furthermore, the board 40 is readily worked and takes a high finish under suitable tools, such as burnishers, edge-setters and the like.

By preference wood flour is employed as the carrier for the waterproofing oil, as it is 45 cheap, easy to handle and non-soluble. Any oil, animal, vegetable or mineral, or any wax, provided heat be employed, may be used as the waterproofing medium. In practice a heavy mineral oil, such as petro- 50 latum, has been successfully employed. A quantity of such oil, say about 150 pounds, is added to 400 pounds of dry wood flour and the two ingredients thoroughly intermingled in a tumbler, revolving barrel or 55 any other mixing machine. Preferably the

oil is warmed, as the wood flour will absorb it more readily when in this condition. This mixture produces a granular mass or filler which, when introduced into the beater engine, will readily mix with the previously shredded leather fibers therein. After the oil-charged mass or filler has been introduced into the beater, the beater is continued in operation long enough to evenly distribute the oil-charged wood flour throughout the leather fibers. This condition of the stock obtains throughout the process of forming the board therefrom. If, however, it should be found, during the process of forming the board, that the oil-charged particles tend to float, the difficulty may be readily removed by the addition of a loading material, preferably inert in the presence of the stock constituents, such as lead oxid, such material being employed in the ratio of about 10 to 15 per cent. of the weight of the wood flour or other vehicle used.

Other oil-carrying vehicles may be employed, and it is readily conceivable that said vehicle may be so heavy that no loading material or substance need be added thereto. The invention, moreover, is not to be limited to the exact steps as above outlined, for the oil may be added directly to the beater stock while the same is being shredded, and the oil-carrying and distributing vehicle introduced simultaneously or thereafter. The direct mixing of the oil and vehicle is, however, preferred, as there can then be no doubt as to the thorough absorption of the oil by the vehicle and the consequent even distribution of the same throughout the mass of fibers.

The term "oil" as employed in the claims is to be given a broad scope; in fact, is to be treated as a generic word including any oil, wax, fat or the like.

Having thus described my invention, what I claim is:

1. The process of producing stock for leather-board, which consists in distributing throughout a mass of shredded leather, an absorptive granular substance charged with oil.

2. The process of producing stock for leather-board, which consists in distributing throughout a mass of shredded leather, a mass of finely-commинuted material charged with oil.

3. The process of producing stock for

- leather-board, which consists in mixing a mass of finely-commинuted material with heated oil, and intermixing the mass thus formed with a mass of shredded leather.
5. 4. The process of producing stock for leather-board, which consists in saturating a mass of wood flour with oil, and mixing such saturated mass with a mass of shredded leather.
10. 5. The process of producing stock for leather-board, which consists in treating wood flour with oil until a granular mass is produced, and finally intermixing the mass with a mass of shredded leather.
15. 6. The process of producing stock for leather-board, which consists in mixing oil with a suitable vehicle; loading the mass thus produced; and finally adding and intermixing said charged and loaded mass with a mass of shredded leather.
20. 7. The process of producing stock for leather-board, which consists in charging a mass of wood flour with oil; loading the same with lead-oxid; and finally intermix-
- ing the loaded, oil-charged mass with a mass 25 of shredded leather.
8. As a new article of manufacture, leather-board having present throughout the same finely-divided absorbent particles charged with oil. 30
9. As a new article of manufacture, leather-board having present throughout the same particles of wood flour charged with oil.
10. As a new article of manufacture, leather-board having present throughout the same loaded and oil-charged particles. 35
11. As a new article of manufacture, leather-board having present throughout the same particles of wood flour charged 40 with oil and loaded with a heavy chemical.

In testimony whereof I have signed my name to this specification in the presence of two subscribing witnesses.

ALBERT L. CLAPP.
